UNITED STATES PATENT OFFICE.

FREDERICK E. KERN, OF ST. LOUIS, MISSOURI.

SHAPING AND IRONING TOOL.

1,418,381.

Specification of Letters Patent. Patented June 6, 1922.

Application filed October 18, 1920. Serial No. 417,707.

To all whom it may concern:

Be it known that I, FREDERICK E. KERN, a citizen of the United States, and resident of St. Louis and State of Missouri, have invented certain new and useful Improvements in Shaping and Ironing Tools, of which the following is a specification containing a full, clear, and exact description, reference being had to accompanying drawings, forming a part thereof.

My invention relates to improvements in shaping and ironing tools and has for its principal object a tool which is designed primarily for the millinery trade, and is adapted to be heated and then used for the shaping of hats or hat trimmings, and may also be used for ironing out portions of the hat which have become crushed in shipping.

In the drawings:

20 Fig. 1 is a side elevation of my device and shows the handle thereof inserted in a hole in the supporting block.

Fig. 2 is a longitudinal, vertical cross sectional view.

25 Fig. 3 is a cross sectional view taken on the line 3—3 of Fig. 1.

Fig. 4 is an elevation of the rod by means of which the head of the tool is secured to the handle.

30 In the construction of my device I make use of a head 5, which is in the shape of an ovoid, the end 6 being blunter than the end 7. This ovoid is provided with a projection 8, which is provided with the screw threaded bore 9. Within this bore 9 is seated the screw threaded portion 10 of the rod 11, the opposite end of the rod 11 is pointed as at 12. This pointed end is firmly driven into the handle 13, which 40 handle has its portion 15 tapered. The tapered portion is adapted to be inserted in a tapered opening 15 formed in the supporting block 16. This block can be placed on any suitable support and is for the purpose 45 of holding the tool in upright position, which is necessary in certain kind of work wherein both hands are required to handle the material being shaped or ironed.

It will be noted that the head 6 is solid, 50 this will enable the head to retain quite an amount of heat and for a relatively long period of time, so that frequent heating is not necessary.

By the use of my device it is possible to 55 take hats which have become dented in shipping and remove these indentations. It is

also possible to change the shape of a hat, or to use the device in ironing bows or other fancy formations of ribbon, or other decorating materials, which are used in the 60 millinery trade.

It will be seen that the head has a top and sides that are curved, the curves of these parts being flat as compared with those of the ends of the head, and these 65 curves merging into rounded ends, that at 7 being a blunt point, and the opposite end, 6, less sharply defined than the pointed end 7. By this construction it is possible with one or another operative portion of the head 70 to reach and operate upon practically any part of a hat, whatever its shape. For instance, to mention but a few of the uses to which my improved shaping tool may be put, it has always been difficult to cover an 75 up-turned brim of a hat smoothly, distributing the necessary fullness of the goods evenly to cover the rim. This work requires stretching of the goods to fit the brim. The necessary fullness can be produced by my 80 tool using the top portion thereof for that purpose. The ends are used in making the angles required in shaping. In making a fold in material used to cover the brim edge of a hat the material must be creased and 85 stretched. For this purpose when operating upon velvet or other heavy goods the material is drawn across the more pointed end of the head of the tool stretching it and at the same time forming the crease. The 90 tool may be used for pressing trimming upon a hat without removing it therefrom, the variously shaped portions permitting it to enter and act upon the different folds and curved parts of such trimming, the hand 95 of the operator being employed to support the trimming while the pressing or ironing takes place.

Having fully described my invention, what I claim is:

1. A shaping and ironing tool for milliners' use comprising an ovoid head adapted to be heated and having its top and sides curved alike and merging in one direction into a rounded end brought to a blunt point, 105 and in the opposite direction to a rounded end less sharply defined than that first mentioned, and a handle by which the head is manipulated.

2. A shaping and ironing tool, comprising 110 an ovoid head, a screw threaded projection formed integral with said head, a screw

threaded rod secured within the projection, a handle secured to the end of said screw threaded rod, the end of said handle being tapered, a supporting block having a 5 tapered opening to correspond with the taper of the handle to hold the tool in upright position.

3. A shaping and ironing tool, comprising a head, said head being so formed as to be 10 circular in cross section and oval in longitudinal section, a screw threaded boss formed integral with said head, a rod pro-

vided with screw threads on one end secured within the screw threaded boss, the opposite end of said rod being tapered and pointed, 15 a handle in which the pointed end of the screw threaded rod is secured, said handle having its end tapered so as to permit its insertion within a means for holding the tool in upright position.

In testimony whereof, I have signed my name to this specification.

FREDERICK E. KERN.
